BURIAL APPARATUS

Walter A. Canaday, Bridgeport, Nebr.

Application September 14, 1949, Serial No. 115,709

4 Claims. (Cl. 27—26)

1
This invention relates to burial apparatus, and more particularly to a mechanism for facilitating the placement of a casket on the conventional casket lowering device.

The object of the invention is to provide a casket placer which is adapted to be detachably connected to the side shafts of a conventional casket lowering device, the placer serving to receive and support the casket, and the placer adapted to be manually disengaged to permit the casket to be deposited upon the lowering straps.

Another object of the invention is to provide a casket placer which includes a pair of frames that will accommodate caskets of various sizes, the casket placer including a simple manually operable locking means for maintaining the frames locked together so as to support the casket prior to depositing the casket on the lowering straps.

Still another object of the invention is to provide a casket placer whose parts move to an out of the way position when the casket is to be deposited on the lowering straps so as not to interfere with the lowering of the casket into the grave.

Still another object of the invention is to provide a casket placer which includes rollers for facilitating and enabling placement of a casket on the lowering straps without the necessity of having pall bearers precariously walking along the sides of the grave, and wherein the funeral director can disengage the casket placer by a simple manual movement to deposit the casket on the lowering straps.

A further object of the invention is to provide a casket placer which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a top plan view of the casket placer, showing it in position upon a casket lowering device;

Figure 2 is a transverse sectional view of the casket placer;

Figure 3 is a view similar to Figure 2, but showing the position of the frame members when these members are swung to a vertical position;

Figure 4 is an enlarged fragmentary sectional view showing one of the fasteners for attaching the casket placer to the lowering device;

Figure 5 is an enlarged side elevational view

2
with parts in section, showing the locking mechanism for connecting the frame members together;

Figure 6 is a fragmentary bottom plan view of a portion of the locking mechanism;

Figure 7 is a sectional view taken on the line 7—7 of Figure 5;

Figure 8 is a sectional view taken on the line 8—8 of Figure 5;

Figure 9 is a sectional view taken on the line 9—9 of Figure 5;

Figure 10 is an enlarged fragmentary plan view showing the mechanism for actuating the lock;

Figure 11 is a sectional view showing certain constructional details of the assembly taken on the line 11—11 of Figure 2;

Figure 12 is an enlarged sectional view taken on the line 12—12 of Figure 1.

Referring in detail to the drawings, there is shown a casket placer for use in facilitating the placement of a casket onto a conventional casket lowering device prior to the lowering of the casket into the grave. The casket lowering device is of ordinary construction and includes a pair of spaced parallel end supports 10 and 11, there being horizontally disposed side shafts 12 and 13 extending between the end supports 10 and 11, Figure 1. The lowering device further includes a pair of spaced parallel flexible lowering straps 14 and 15 which extend between the side shafts 12 and 13 and are connected thereto.

The device of the present invention serves to facilitate the placement of the casket onto these lowering straps and the placement device comprises a pair of casket supporting frames 16 and 17. The frame 16 includes a pair of spaced parallel end bars 18 and 19 and extending between the bars 18 and 19 and secured thereto, is a tubular brace member 20. Projecting upwardly from the end bar 18 and secured thereto, as by welding, is a bracket 21 which supports a rotatable roller 22. A similar bracket projects upwardly from the other end bar 19, the bracket being designated by the numeral 23. The bracket 23 serves to rotatably support a roller 24 thereon.

Extending between the brackets 21 and 23 and secured thereto, is a tubular brace member 25 which coacts with the member 20 to maintain the parts of the frame 16 in proper spaced relation.

The frame 16 is adapted to be hingedly connected to the side shaft 12 of the lowering device so that the frame 16 can move to the position shown in Figure 3 when the casket is to be deposited onto the straps 14 and 15. For providing this pivotal or hinged connection, a hook

member 26 projects from the bar 18 and slidably embraces the shaft 12. A similar hook member 27 projects from the other end bar 19 for engagement with the shaft 12. A fastener is provided for coacting with these hook members to prevent the frame 16 from accidentally working loose from the shaft 12 during its swinging movement. This fastener includes a clasp 28 which has a bent portion 29, Figure 4, and the bent portion 29 is adapted to be inserted into an opening 30 in the hook member 26 or 27. A coil spring 31 has one end connected to the clasp 28 and its other end connected to the hook member, and the coil spring serving to prevent the bent portion 29 from accidentally working out of the opening 30.

The other frame 17 includes a pair of spaced parallel end bars 32 and 33 which are connected together by means of a tubular brace member 34. Projecting upwardly from the end bar 32 and secured thereto, is a bracket 35 which supports a rotatable roller 36 thereon. A similar bracket 37 projects from the end bar 33 and the bracket 37 supports a rotatable roller 38. A tubular brace member 39 extends between the brackets 35 and 37 and is secured thereto, the members 34 and 39 coacting to maintain the parts of the frame in proper spaced relation.

The frame 17 includes a pair of hook members 40 and 41 which serve to provide a pivotal connection of the frame 17 to the side shaft 13 of the lowering device. A fastener, having the same construction as the fastener shown in Figure 4, coacts with each of the hook members 40 and 41 for preventing the frame 17 from accidentally working loose from the shaft 13.

When the frames 16 and 17 are in their horizontal position, as shown in Figures 1 and 2, the casket is adapted to be supported on the rollers 22, 24, 36, and 38. To maintain these frames in this position, there is provided a locking mechanism which is adapted to be controlled by the funeral director. The locking mechanism is shown in detail in Figures 5 through 10 and includes a keeper 42 which is slidably positioned in a recess 9 that is formed in the bottom of the end bar 18, there being a pair of flanges 43 and 44 for insuring that the keeper 42 moves properly in the recess 9. A pin 45 is carried by the keeper 42 and the pin 45 is adapted to contact the flange 44 to limit forward movement of the keeper 42.

The keeper 42 further includes a shoulder 46 and the keeper has a pointed end 47. A coil spring 48 is interposed between the shoulder 46 and the end of the bar 18 for a purpose to be later described. The pointed end 47 of the keeper is adapted to project into an open end of a sleeve 49, the sleeve 49 being adjustably or slidably arranged on the bar 32. A flange 50 is secured to the sleeve 49 and the flange 49 is adapted to be engaged by the pointed end 47 of the keeper whereby pivotal or swinging movement of the frames 16 and 17 is prevented as when these parts are in the position shown in Figure 5. For maintaining the sleeve 49 immobile in its adjusted position on the bar 32, a set screw 51 projects through the sleeve and into engagement with the bar 32.

Slidably arranged on the bar 33 is a sleeve 52, Figure 1, there being a set screw 53 for maintaining the sleeve 52 immobile in its adjusted position on the bar 33. Slidably carried by the bar 19 is a keeper which has the same construction as the previously described keeper 42, and

the sleeve 52 is adapted to receive the keeper carried by the bar 19.

A manually operable means is provided for disengaging the keepers from the sleeves 49 and 52 whereby the frames 16 and 17 will swing to the vertical position of Figure 3. This means includes a chain 54 which has a ring 55 connected to one end thereof and the ring 55 is adapted to be gripped in the funeral director's hand when the casket is to be deposited onto the lowering straps 14 and 15. The other end of the chain 54 is connected to a bushing 56 and a pin 57 pivotally connects an end of an L-shaped link 58 to the bushing 56. A securing element 59 pivotally connects the link 58 to the bar 19 and a coil spring 60 has one of its ends connected to the link 58 and its other end connected to the bar 19. A rod 61 has one of its ends connected to the link 58 and its other end connected to the keeper which engages the sleeve 52.

The keeper 42 is moved or retracted at the same time that the other keeper is retracted or moved out of engagement with the sleeve 52 and for accomplishing this, a rod 62 is connected to the keeper 42. The rear end of the rod 62 is connected to an L-shaped link 63 and an elongated rod 64 connects the link 63 to the bushing 56.

In use, the conventional lowering device is positioned over the grave as shown in Figure 1. Then, the placement of the casket on the flexible straps 14 and 15 is readily accomplished by means of the device of the present invention. Thus, the frames 16 and 17 are arranged horizontally as shown in Figures 1 and 2, the hook members 26 and 27 being arranged in engagement with the side shaft 12 while the other hook members 40 and 41 are arranged in engagement with the other shaft 13 of the lowering device. The clasps 28 coact with these hook members to prevent the frames from accidentally working loose from the shafts 12 and 13 during pivotal movement of the frames. The device of the present invention eliminates the necessity of having the pall bearers walking precariously along the sides of the grave since the casket can be properly placed by positioning the casket on the rollers 24 and 38, or the rollers 22 and 36. Then, the casket can be readily moved longitudinally across the grave so that the casket will be finally supported by all four of the rollers 22, 36, 24, and 38. Now, to deposit the casket onto the straps 14 and 15, the funeral director pulls the chain 54. This results in movement of the rod 64. Thus, the links 58 and 63 are simultaneously pivoted to thereby retract the keeper 42 out of engagement with the sleeve 49 and also move the other keeper out of engagement with the sleeve 52. As these keepers are retracted, the frames become free to pivot or swing from their horizontal position to their vertical position whereupon the casket will be deposited on the straps 14 and 15 so that the casket can be lowered into the grave. Normally the springs 48 and 60 urge the pointed ends 47 of the keepers into their locking position of Figure 5. By proper positioning of the sleeves 49 and 52, the placement device can be adjusted to accommodate various sizes of caskets and the device can be extended to fit graves of different widths.

By using the device of the present invention, the funeral director can place the casket on the lowering device with ease and dispatch, no special tools being needed to accomplish this. The casket placer is simple in construction and light in weight and can be manufactured with ease and inexpensively.

What I claim:

1. In a burial apparatus, the combination with a lowering device including a pair of spaced parallel side shafts, and flexible straps extending between said shafts, of a means for facilitating the placement of a casket on said straps, said means comprising a pair of frame members mounted for swinging movement about a horizontal axis, each of said frame members comprising a pair of spaced parallel end bars, hook members projecting from the ends of said bars and adapted to pivotally engage said side shafts, fasteners coacting with said hook members for locking said frame members onto said shafts, tubular brace members extending between said end bars and secured thereto, a bracket projecting upwardly from each of said end bars and secured thereto, a tubular member extending between said brackets and secured thereto, a roller carried by each of said brackets, and locking means for maintaining said frame members in horizontal casket supporting position.

2. The apparatus as described in claim 1 and further including manually operable means for actuating said locking means.

3. In a burial apparatus, the combination with a lowering device including a pair of spaced parallel side shafts, and flexible straps extending between said shafts, of a means for facilitating the placement of a casket on said straps, said means comprising a pair of frame members mounted for swinging movement about horizontal axes, each of said frame members comprising a pair of spaced parallel end bars, hook members projecting from the ends of said bars and adapted to pivotally engage said side shafts, fasteners coacting with said hook members for locking said frame members onto said shafts, a tubular brace member extending between said end bars and secured thereto, a bracket projecting upwardly from each of said end bars and secured thereto, a tubular member extending between said brackets and secured thereto, a roller carried by each

5
10
15
20

of said brackets, locking means for maintaining said frame members in horizontal casket-supporting position, and manually operable means for actuating said locking means, said manually operable means comprising a chain having a ring connected to one end thereof and adapted to be gripped in a person's hand, a bushing connected to the other end of said chain, an L-shaped link having one end pivotally connected to said bushing, and means connecting the other end of said link to said locking means.

4. In a burial apparatus, a pair of spaced parallel side shafts, a pair of frame members mounted for swinging movement about horizontal axes, each of said frame members comprising a pair of spaced parallel end bars, hook members projecting from the ends of said bars and adapted to pivotally engage said side shafts, fasteners coacting with said hook members for locking said frame members onto said shafts, a tubular brace member extending between said end bars and secured thereto, a bracket projecting upwardly from each of said end bars and secured thereto, a tubular member extending between said brackets and secured thereto, a roller carried by each of said brackets, locking means for maintaining said frame members in horizontal casket-supporting position, and manually operable means embodying a chain for actuating said locking means.
